UNITED STATES PATENT OFFICE.

WILLIAM B. MARTIN, OF BLOOMINGTON, ILLINOIS.

CONCRETE-MIXER.

No. 820,428.

Specification of Letters Patent.

Patented May 15, 1906.

Application filed October 10, 1905. Serial No. 282,172.

To all whom it may concern:

Be it known that I, WILLIAM B. MARTIN, a citizen of the United States, residing at Bloomington, in the county of McLean and State of Illinois, have invented a new and useful Concrete-Mixer, of which the following is a specification.

This invention relates to concrete-mixers, and is designed as an improvement upon a machine of similar character for which I received Letters Patent in the United States, dated August 8, 1905, No. 796,591.

The object of the present invention is to simplify and improve the construction of the machine and to increase its efficiency.

With the above and other objects in view, as will appear as the nature of the invention is better understood, the same consists in the novel construction and combination of parts 20 of a concrete-mixer, as will be hereinafter fully described and claimed.

In the accompanying drawings, forming a part of this specification, and in which like characters of reference indicate corresponding parts, Figure 1 is a view in side elevation of a machine constructed in accordance with the present invention. Fig. 2 is a view in end elevation of the front portion of the machine, the rear portion being omitted. Fig. 30 3 is a fragmentary detail view in section, on an enlarged scale, of the discharge portion of the apparatus.

Referring to the drawings, 1 designates generally the casing of the apparatus, which 35 is preferably rectangular in horizontal section and may be constructed of any suitable material adapted to the purpose.

Projecting from one side of the casing and communicating with the interior thereof is a 40 discharge-spout 2, combined with the free or exit end of which is a scoop-shaped lip 3, hereinafter fully described. The spout is supported from the casing by a pair of horizontally-disposed brace-rods 4^a, only one of 45 which is shown, and by a pair of angularly-disposed brace-rods 5, the lower ends of which are secured to the rods 4^a and the upper ends to the casing.

One of the salient features of the present 50 invention is the provision of means whereby the material within the spout shall be prevented from escape until thoroughly mixed. This function is secured by means of a metal plate 6, which is cut away to conform to the exterior of the lip, the latter being provided with a flange 4, which is bolted or riveted to

the plate and is therefore rigid therewith. The plate works at its ends between guides 7, each of which is constructed of a bar of metal bent into an approximately U-shape and one 60 member of each of which is secured to the sides of the spout by bolts or rivets 8. Combined with each of the guides is a series of rollers 9, between which the plate works and is guided for vertical movements when the 65 plate is raised or lowered, to effect which there is a lever 10 provided that is fulcrumed upon a standard 11, secured to the upper side of the spout and has its free end connected with a bail 12, the terminals of which 70 are secured to the plate at 13. It will of course be understood that the plate 6 will be disposed close to the end of the spout, so that when the lip 3 is raised it will close the gap formed between the rear portion of the lip 75 and the spout, and thereby prevent escape of material.

In the patent referred to the spout is a cylindrical structure; but in the present instance it is shown as having an open top, as 80 at 14, which will leave the worm 15 exposed. This latter may be constructed the same as that described in the patent or may be of any other preferred type. The object for leaving the top of the casing open is to facilitate application of water to the contents of the spout, and herein resides another feature of improvement. In the patent referred to the sprinkling of the concrete is effected within 85 the casing by means of a perforated water-pipe projecting therein. In the present invention the water-pipe 16 only extends part of the length of the spout and is supported over the open portion thereof by brackets 17. The pipe has perforations which are arranged 90 in parallel rows, the object of the arrangement being to permit the cutting off of a portion of the flow of the water if desired. This is effected by means of a semicircular cut-off 18, which is suitably combined with the pipe 100 and is provided with a handle 19, by which it may be turned. Of course this cut-off closely impinges the pipe, and it will be seen that by turning it the escape of the water may accurately be controlled.

The final feature of improvement in the present invention over that in the patent is in driving the worm directly from the source of power instead of by a sprocket-chain, as shown in the patent to which reference has 110 been made, and this is effected by placing upon the shaft 20 of the worm a pulley 21,

around which is passed a belt to a suitable source of power.

The improvements herein defined, while simple in character, will be found thoroughly efficient for the purposes designed and will in 5 a practical and positive manner secure the objects sought.

Having thus described the invention, what is claimed is—

10 1. In a concrete-mixer, the combination with a spout, of guides disposed at the discharge end thereof and provided with roller-bearings, a cut-off plate having its ends working between the bearings, a lip secured to the 15 plate, and means for raising and lowering the plate.

20 2. In a concrete-mixer, the combination with a spout, of guides disposed at the discharge end thereof and occupying a plane at right angles to its length, roller-bearings carried by the guides, a cut-off plate having its ends working between the bearings, a lip secured to the plate, and means for raising and lowering the plate.

3. In a concrete-mixer, the combination 25 with a spout, of guides disposed at the discharge end thereof and occupying a plane at right angles thereto, roller-bearings carried by the guides, a cut-off plate having its ends working between the bearings, a lip carried 30 by the plate, and means for raising and lowering the plate.

4. In a concrete-mixer the combination with a spout having its upper portion open for a part of its length and a mixing-worm 35 arranged within the spout; of guides disposed at the discharge end of the spout and provided with roller-bearings, a cut-off plate having its ends working between the bearings, a lip secured to the plate, and means for rais- 40 ing and lowering the plate.

In testimony that I claim the foregoing as my own I have hereto affixed my signature in the presence of two witnesses.

WILLIAM B. MARTIN.
